UNITED STATES PATENT OFFICE.

THOMAS J. HAYES, OF BOSTON, MASSACHUSETTS.

BELT CUTTING AND PUNCHING TOOL.

1,179,830.

Specification of Letters Patent. Patented Apr. 18, 1916.

Application filed October 23, 1915. Serial No. 57,456.

To all whom it may concern:

Be it known that I, THOMAS J. HAYES, a citizen of the United States, residing at Boston, in the county of Suffolk and State of Massachusetts, have invented new and useful Improvements in Belt Cutting and Punching Tools, of which the following is a specification.

This invention relates to tools for cutting off the ends of round leather belting to form square ends adapted to be abutted together, for punching the belting near said ends to form holes for the reception of the legs of a staple-shaped wire coupling, and for 10 clenching the legs of the coupling upon adjacent ends of the belting. A tool of this character in common use comprises a pair of jaws having opposed faces between which the belting is grasped, and crossed levers ful- 15 crumed together between the jaws, and so connected with the jaws that the faces there- of are moved toward and from each other by the levers and are maintained in parallelism with each other, one of the jaws being 20 provided with a perforating punch and with a cutter projecting inwardly from the jaw and coöperating with a shearing edge at one end of a belt-receiving recess in the other jaw in cutting off the end of a length of 25 belting interposed between the jaws, the jaws being provided with extensions formed to coöperate in clenching the belt coupling. Heretofore the cutter of a tool thus char- 30 acterized has been rigidly attached to the jaw which carries it, and has been so arranged 35 that its cutting edge is liable to be injured by contact with a belt coupling between said extensions and is not adapted to be ground away to any considerable extent to com- 40 pensate for wear.

My invention has for its object to obviate these defects and to enable the cutter to operate with less resistance than heretofore.

The invention also has for its object to 45 provide a tool of this character with im- proved means for stripping the belting from the punch, and for centralizing the belting relatively to the punch.

To these and other related ends the inven- 50 tion consists in the improvements which I will now proceed to describe and claim.

Of the accompanying drawings forming a part of this specification: Figure 1 represents a side elevation of a tool constituting 55 a simple embodiment of my invention, the jaws being opened; Fig. 2 represents an edge

view of the same; Fig. 3 represents an elevation of the opposite side of the tool, the jaws being closed; Fig. 4 represents a side view of the cutter detached; Fig. 4^a represents a fragmentary view of a modification; Fig. 4^b represents an enlarged section on line 4^b—4^b of Fig. 1; Figs. 5 to 12 inclusive show another embodiment of the invention; Fig. 5 represents a side elevation, the jaws being opened; Fig. 6 represents an edge view; Fig. 7 represents a side view, the jaws being closed; Fig. 8 represents an elevation of the opposite side, the jaws being closed; Figs. 9 and 10 represent respectively a side and an edge view of the cutter detached; Fig. 11 represents a section on line 11—11 of Fig. 5; Fig. 11^a represents a plan view of the stripping member detached; Fig. 12 represents a section on line 12—12 of Fig. 5; Fig. 13 represents a side elevation of a third embodiment of the invention, the jaws being opened; Fig. 14 represents an edge view of the tool shown by Fig. 13; Fig. 15 represents an elevation of the opposite side of the tool shown by Fig. 13, the jaws being closed; Fig. 16 represents a section on line 16—16 of Fig. 13.

The same reference characters indicate the same or similar parts in all the views.

Referring first to Figs. 1, 2, 3 and 4: In the drawings, 12 and 13 represent the jaws of a belt-cutting and punching tool, said jaws being termed for convenience of description the upper and the lower jaw re- 90 spectively, although it is obvious that the tool may be used with either jaw upper- most. 14 and 15 represent crossed levers fulcrumed together at 16 between the jaws, each lever having a longer and a shorter 95 arm. The shorter arms of the levers are connected with the jaws by pivot studs 17, lo- 100 cated in sockets in the jaws formed to closely fit the studs. The longer arms of the levers are engaged with the jaws by studs 18, lo- 105 cated in longitudinal slots 19 in the jaws, the arrangement being such that when the levers are moved from the position shown by Fig. 1 to that shown by Fig. 4, the jaws are closed and are constantly maintained 110 parallel with each other. The upper jaw has a punch 20 arranged to enter an orifice 20^a in the lower jaw when the jaws are closed. The jaws are provided with cou- 115 pling-clenching extensions 12^a and 13^a ad- jacent to the punch. The lower jaw is pro- vided with a recess 30 to receive a portion

of the belting, the intersection of the wall of said recess with one side of the jaw forming a shearing edge.

The construction thus far described is well known and is not claimed by me, this embodiment of my invention relating to the improvements next described in the cutter, and to the means for stripping the belting from the punch, and for centralizing the belting for the action of the punch.

The cutter, which is shown separately by Fig. 4, is composed of a blade 22 and an elongated shank 22^a. Said shank has a longitudinal slot 23 at one end which receives a stud 24 fixed to the upper jaw. The opposite end of the shank has a socket or orifice 25 which receives and surrounds the stud 18 connected with the lever 14. Said studs 24 and 18 maintain the cutter shank in a position parallel with the upper jaw, and the slot 23 permits the cutter to be moved endwise on the upper jaw from the position shown by Fig. 1 to that shown by Fig. 3 when the jaws are closing, the cutter also moving with the upper jaw toward the lower jaw. The cutter has an oblique cutting edge 26 which projects from the upper jaw and is inclined relatively thereto, said edge being arranged to move in sliding contact with one side of the lower jaw and cooperate with the shearing edge on said jaw, in cutting a length of belting interposed between the jaws. The described movements of the cutter cause its edge to make an oblique shearing cut with the minimum expenditure of power. The arrangement of the cutting edge is such that it is guarded by the back 27 of the blade against contact with a belt coupling between the extensions 12^a, 13^a, hence there is no liability of injury to the cutting edge by the coupling. This arrangement also enables the cutting edge to project considerably below the upper face of the lower jaw when the jaws are closed, as shown by Fig. 3, so that the edge may be considerably reduced by repeated grindings without being rendered inoperative. The shank 22^a is preferably provided with an additional slot 28 to receive the stud 17.

50 The above described belt-receiving recess 30 in the lower jaw coincides with the punch 20.

31 represents a belt-stripping member composed of a resilient metal strip attached at 32 to the lower jaw and having a free end portion projecting over the recess 30, said portion having an orifice through which the punch passes.

The free end of the stripping member is adapted to bear yieldingly on the upper side of belting located in the recess and to strip the belting from the punch when the jaws are opened. The upper jaw is preferably provided with a stud 35^a passing through

70 an orifice in the stripping member and having a head 36^a of greater diameter than said orifice and bearing against the under side of said member, the arrangement being such that when the jaws are opened the stud lifts the stripping member from a belt in the recess 30. The free end of the stripping member is preferably curved to conform to the upper side of the belting on which it bears, and coöperate with the similarly curved recess 30 in holding the belting central relatively to the punch and preventing liability of punching the belting out of center.

75 The belt-receiving recess in the lower jaw may be angular, as indicated at 30^a (Fig. 4^a), the free end of the stripping member being correspondingly formed.

80 The punch 20 is preferably oblong or elliptical in cross section, as indicated by Fig. 2, the longer axis of its cross section being parallel with the belt. I find that this form is better than a circular form, because it enables the punch to penetrate and withdraw from the belt with less resistance, reduces to the minimum the lateral bulging of the belt at opposite sides of the punched hole, and enables the punch to be secured in the socket provided for its reception in the upper jaw without liability of turning therein. Said socket may be formed by a groove 35^b formed in the jaw 12, and a 90 groove 35^a formed in a plate secured to said jaw, as shown by Fig. 4^b.

95 The embodiment of the invention shown by Figs. 5 to 12 inclusive is distinguished from the simpler embodiment above described in the particulars next described.

100 The upper jaw 12 is provided with a fixed shearing edge 33 formed, as shown by Figs. 5 and 6, by the intersection of one side of the jaw with one side of the wall of a recess 34 formed in the jaw. The cutter 22 is provided at its upper edge with a wing or projection, one side of which is sharpened to form a movable cutting or shearing edge 35 adapted to coöperate with the fixed edge 33 105 in severing a piece of belting placed in said recess. I call the edges 33 and 35 supplemental cutting edges to conveniently distinguish them from the cutting edge 26 and the side of the jaw with which it coöperates. The object of these supplemental cutting edges is to sever the leading end of a length of belting wound on a spool, without punching the belting. The shank 22^a of the cutter is provided with a curved extension 37 having an 110 orifice 38 which receives a stud or pin 39 attached to the lever 14 at such distance from the fulcrum pin 16 that the closing movement of the jaws gives the cutter a greater longitudinal movement than is the case when the cutter shank is engaged with a pin 19, as shown by Figs. 1 and 3. The longitudinal movement thus imparted to the cutter is sufficient to cause the coöperation of the supplemental cutting edges 33 and 35. The 115

120 125 130

punch 20, instead of being immovably attached to the upper jaw as in the first described embodiment of the invention, is attached to a carrier 40 (Fig. 11), which is 5 movable crosswise of the upper jaw 12 in a guide or socket 41 formed in said jaw, the punch being therefore adjustable toward and from the cutter 22, so that the fastener-receiving hole formed by the punch may be at 10 a greater or less distance from the cut end of the belting, provision being therefore made for using fasteners of different sizes. The carrier 40 may be adjusted and held at 15 adjustments by any suitable means. As here shown, an adjusting screw 43 is engaged with a tapped socket 44 in the jaw 12 above the guide 41, said screw having a shank projecting from one side of the jaw and provided with a flange 46 engaging a groove 47 20 in the carrier 40, and with a head 48 whereby the screw may be rotated to adjust the carrier and punch. The punch-receiving orifices in the jaws 12 and 13 and in the stripping member are elongated, as shown by 25 Fig. 11, to permit the desired adjustments of the punch. The stripping member in this embodiment of the invention, instead of being formed on a resilient metal strip supported by the lower jaw as in the first 30 described embodiment, is an arm 31^a bridging the belt-receiving recess in the lower jaw and having a perforated ear 50 (Fig. 11^a) attached to a sectional stud, which is preferably composed of a lower section 51, the 35 upper end of which bears on the lower side of said ear, and an upper section 52 having a reduced threaded lower end passing through the ear 50 and screwed into the section 51, the section 52 having a shoulder 40 bearing on the upper side of said ear, which 45 is thus clamped between the two sections. The lower section of the stud has a sliding fit in an orifice 53 in the lower jaw, and the upper section 52 has a sliding fit in an orifice formed in a threaded bushing 54 screwed into the upper jaw. The upper end of the upper section is threaded and is provided with a stop nut or nuts 55 held by a 50 spring 56 against the upper side of said bushing. The spring surrounds the upper section 52 and bears at its upper end on the bushing 54, which constitutes a fixed abutment. The lower end of the spring bears on the ear 50 and acts to hold the stop nut 55 seated on the bushing 54, when the jaws are 55 opened, the stripping member 31^a being held yieldingly in its initial position bridging the mouth of the recess 30, as shown by Fig. 5. By turning the nut 55 the stud and stripping 60 member may be slightly raised or lowered to give it the exact initial position shown, in case it is found that, owing to imperfections in the form and assemblage of the levers and jaws, the initial position of the stripping 65 member requires adjustment, it being desir- able that the stripping member and lower jaw shall stand in the relative positions shown by Fig. 5 when the jaws are opened. When the jaws are closing the spring acts to force the stripping member into the recess 70 30, as shown by Fig. 7, until the stripping member bears on a belt in said recess, the spring then yielding until the jaws are fully closed, and the outer ends of the stud sections being projected from the jaws to 75 an extent determined by the diameter of the belt. When the jaws are opened the bushing 54 abuts against the nut 55 and raises the stripping member from the belt against the pressure of the spring. The lower stud 80 section 51 is provided with a head 58, which abuts against a shoulder on the lower jaw when the jaws are fully opened, as shown by Fig. 12.

The described construction enables me to 85 employ a spring 56 of sufficient length to exert pressure on the stripping member ahead of the punch and before the stripping member contacts with the belt, the pressure of the spring increasing as the punch 90 enters the belt and causing the stripping member to effectively perform its function.

In the embodiment of the invention shown by Figs. 13, 14, 15, and 16, I have substituted for the rectilinearly moving cutter 95 previously described, a cutter 60, which is pivoted at 61 to oscillate on the upper jaw, and has a curved cutting edge 62 adapted to coöperate with one side of the lower jaw, 100 said cutting edge being eccentric to the center of oscillation. In place of the spring-pressed stripping member a fixed stripping member 63 may be employed, this being a curved bridge integral with or rigidly attached to the lower jaw and forming the 105 top of a circular opening 64 formed to receive the belt. An arm or ear 65 on the cutter is pivoted at 66 to one end of a link 67 the other end of which is pivoted at 68 to the lever 14, the arrangement being such 110 that when the jaws are opened, as shown by Fig. 13, the cutting edge 62 is outside the opening 64, and when the jaws are closed, as shown by Fig. 15, the cutting edge swings 115 in a curved path entirely across said opening. The punch carrier 40 in this embodiment of the invention is provided with two or more grooves 70 (Fig. 16), either of 120 which is adapted to receive the inner arm of a latch or detent 71, which is pivoted at 72 to the upper jaw. A spring 73, acting on the outer arm of said detent, holds its inner arm in engagement with a groove 70 in the punch carrier, which is adapted to be 125 locked in different positions. The carrier is preferably held normally at one extreme of its movement by a spring 74 housed in a socket in the upper jaw and pressing outwardly on an arm 75 fixed to the carrier.

It will be seen that in each of the de- 130

scribed embodiments of the invention the belt cutting edge of the cutter projects from the upper jaw to coöperate with a shearing edge at one end of a belt-receiving recess in 5 the lower jaw and has a compound movement due first to its connection with the upper jaw whereby the cutter is caused to move with said jaw toward and from the shearing edge of the lower jaw, and secondly to its connection with one of the levers constituting the jaw-operating mechanism whereby the cutter is given an additional movement either in a rectilinear path or in a curved path, while coöperating with 10 said shearing edge. The said compound movement in either case reduces to the minimum the force required to impel the cutter through the belt.

In each embodiment of the invention the 20 cutting edge coöoperating with the lower jaw is guarded by the back of the cutter, because said back faces the open end of the space between the coupler-clenching extensions of the jaws and extends substantially across 25 said space when the jaws are opened, so that it prevents a belt coupler in said space from touching the cutting edge.

Having described my invention, I claim:

1. A tool of the character stated, comprising an upper and a lower jaw, said 30 jaws having opposed inner faces and the lower jaw having in its inner face a belt-receiving recess the wall of which intersects one side of the lower jaw to form a shearing edge, jaw-operating means maintaining the jaws parallel, a cutter movably connected with the upper jaw and bodily movable thereby, said cutter having a cutting edge projecting inwardly from the upper jaw and 35 in sliding contact with the said shearing edge, and means connecting the cutter with the jaw-operating mechanism whereby an additional cutting movement is imparted to the cutter when the jaws are closing and 40 while the cutter is coöperating with said shearing edge.

2. A tool of the character stated, comprising an upper and a lower jaw, said jaws having opposed inner faces including coupler-clenching faces, and the lower jaw having in its inner face a belt-receiving recess the wall of which intersects one side of the lower jaw to form a shearing edge, jaw-operating means maintaining the jaws parallel, and a cutter connected with and movable by the upper jaw, said cutter having a cutting edge projecting inwardly from the upper jaw and in sliding contact with the said shearing edge, and a back facing the 50 open end of the space between said extensions and arranged to guard said cutting edge.

3. A tool of the character stated, comprising an upper and a lower jaw, said jaws 60 having opposed inner faces including cou-

pler-clenching extensions and the lower jaw having in its inner face a belt-receiving recess the wall of which intersects one side of the lower jaw to form a shearing edge, jaw-operating means maintaining the jaws parallel, a cutter movably connected with the upper jaw and bodily movable thereby, said cutter having a cutting edge projecting inwardly from the upper jaw and in sliding contact with the said shearing edge, a back facing the open end of the space between said extensions and arranged to guard said cutting edge, and means connecting the cutter with the jaw-operating mechanism whereby an additional cutting movement is imparted to the cutter when the jaws are closing and while the cutter is coöperating with said shearing edge.

4. A tool of the character stated, comprising an upper jaw, a lower jaw having a belt-receiving recess, a punch carried by the upper jaw and arranged to enter said recess, an independently movable stripping member bridging the recess and apertured to receive the punch, and resilient means connecting the stripping member with the tool and permitting the stripping member to yield and hold belts of different sizes against the bottom of the recess when the jaws are closing.

5. A tool of the character stated, comprising an upper jaw, a lower jaw having a belt-receiving recess, a punch carried by the upper jaw and arranged to enter said recess, and a spring-pressed stripping member bridging said recess and adapted to bear yieldingly on a belt therein, said member being formed to centralize a belt in said recess.

6. A tool of the character stated, comprising an upper jaw, a lower jaw having a belt-receiving recess, a punch carried by the upper jaw and arranged to enter said recess, a spring-pressed stripping member bridging said recess and adapted to bear yieldingly on a belt therein, and means carried by the upper jaw for raising said member when the jaws are opened.

7. A tool of the character stated, comprising an upper jaw, a lower jaw having a belt-receiving recess, a punch carried by the upper jaw and arranged to enter said recess, a spring-pressed stripping member bridging said recess and adapted to bear yieldingly on a belt therein, and means carried by the upper jaw for raising said member when the jaws are opened, said means having provisions for adjusting the stripping member to establish a correct initial position thereof.

8. A tool of the character stated, comprising an upper jaw having a stud guide, a lower jaw having a belt-receiving recess and a stud guide alined with the stud guide in the upper jaw, a stripping member formed to bridge said recess, a stud attached 130

to said stripping member and projecting into said guides, and a spring arranged to exert downward pressure on the stripping member and stud, the upper end of the stud 5 being provided with an adjustable stop member held yieldingly against the stud guide of the upper jaw by said spring.

9. A tool of the character stated, comprising an upper jaw, a lower jaw having a 10 belt-receiving recess, and a punch carried by the upper jaw and arranged to enter said recess, the punch being oblong in cross section and arranged with the longer axis of its cross section parallel with a belt in said 15 recess.

10. A tool of the character stated, comprising upper and lower jaws, a cutter carried by the upper jaw and having a cutting edge coöperating with the lower jaw, a 20 punch movably connected with the upper jaw, and means for adjusting the punch crosswise of said jaw.

11. A tool of the character stated, comprising upper and lower jaws, a cutter carried by the upper jaw and having a cutting edge coöperating with the lower jaw, the 25 upper jaw being provided with a punch carrier guide, a punch carrier in said guide provided with a punch arranged to enter said 30 recess, and means for adjusting said carrier and punch crosswise of the jaw.

12. A tool of the character stated, comprising upper and lower jaws, crossed levers fulcrumed together between the jaws and 35 engaged therewith to maintain the jaws in parallelism, a cutter having an elongated shank, and connections between the said shank, the upper jaw, and one of said levers, whereby, when the jaws are closed or 40 opened, the cutter is moved with the upper jaw toward or from the lower jaw, and is also moved rectilinearly lengthwise of the upper jaw, the cutter being provided with a cutting edge projecting obliquely from the 45 upper jaw and coöperating with the lower jaw.

13. A tool of the character stated, comprising upper and lower jaws, crossed levers fulcrumed together between the jaws and 50 engaged therewith to maintain the jaws in parallelism, a cutter having an elongated

shank, and connections between the said shank, the upper jaw, and one of said levers, whereby, when the jaws are closed or 55 opened, the cutter is moved with the upper jaw toward or from the lower jaw, and is also moved rectilinearly lengthwise of the upper jaw, the cutter being provided with a cutting edge projecting obliquely from the upper jaw and coöperating with the lower 60 jaw and with a back arranged to guard the cutting edge.

14. A tool of the character stated, comprising upper and lower jaws, crossed levers fulcrumed together between the jaws and 65 engaged therewith to maintain the jaws in parallelism, a cutter having an elongated slotted shank which is pivoted to one of said levers and connected with the upper jaw to have a rectilinear longitudinal movement 70 thereon, one end portion of said shank being fulcrumed to one of said levers, the cutter being provided with a cutting edge projecting obliquely from the upper jaw and coöperating with the lower jaw, and with a 75 back arranged to guard the cutting edge.

15. A tool of the character stated, comprising upper and lower jaws, jaw-operating means maintaining the jaws parallel, a cutter having a cutting edge coöperating 80 with the lower jaw, and a supplemental cutting edge coöperating with the upper jaw, and connections between the cutter, the upper jaw and the operating means whereby a compound movement is imparted to the 85 cutter.

16. A tool of the character stated, comprising an upper jaw, a lower jaw, each of said jaws having a transverse belt-receiving recess and a cutting edge at one end of said 90 recess, jaw-operating means maintaining the jaws parallel, a cutter carried by the upper jaw and having a lower cutting edge coöperating with the lower jaw, and an upper supplemental cutting edge coöperating with 95 the upper jaw, and connections between the cutter, the upper jaw, and the jaw-operating means whereby a compound movement is imparted to the cutter.

In testimony whereof I have affixed my 100 signature.

THOMAS J. HAYES.
